CARBON PAPER HOLDER FOR MANIFOLDING
TYPEWRITERS

Joseph Carroll Doyle, Rochester, N. Y., assignor
to Kee Lox Manufacturing Company, Rochester, N. Y., a corporation of New York

Application February 16, 1951, Serial No. 211,352

6 Claims. (Cl. 282—1)

1

This invention relates to a carbon paper holder for manifolding typewriters of the type in which a series of sheets of carbon paper are each connected to a separate supporting bar or blade of a movable carbon paper carriage and interposed between continuous sheets of paper on which typewritten records are to be made, the carbon paper carriage being withdrawn after each typing operation to remove the carbon sheets from between and permit tearing off the typewritten records from the continuous record sheets, and it has for its principal purpose to afford a structure including a holder that can be permanently fastened to a supporting bar of the carbon paper carriage and a carbon paper pack that is detachably associated with the holder whereby the carbon paper pack can be renewed when all of the carbon paper sheets are used by detaching the carbon paper pack from the holder, without the necessity of removing the holder or otherwise disturbing the relationship between the holder and the supporting bar.

A further purpose of the invention is to afford a construction adapted for convenient use with a carbon paper pack consisting of a multiplicity of sheets of carbon paper attached at one end to a backing sheet and each sheet of carbon paper folded upon itself and arranged flatwise, with means for detachably securing such a carbon paper pack to a holder.

An additional object of the invention is to afford a structure of simple and economical manufacture in which a multiplicity of folded carbon sheets are attached to a backing sheet and the backing sheet constructed so that it can be readily attached to a holder mounted on the supporting bar of the carbon paper carriage, or removed therefrom as required.

Still another purpose of the invention is to afford a structure in which a backing sheet with a plurality of folded carbon sheets secured thereto is detachably associated with a holder permanently mounted on the supporting bar and which can be easily secured to or removed from the holder by the operator while also providing means for effectively protecting the folded carbon sheets in the pack from contact with the record sheets as the carbon paper carriage is moved rearwardly of the record sheets.

A further object of the invention is to afford a simple, practical, and economical construction comprising a flexible holder that may be permanently attached to the supporting bar of the carbon paper carriage and which is so constructed as to receive and hold the backing sheet

2

of the carbon pack, the backing sheet and carbon pack having provision for readily associating these parts with the flexible holder or removing them when the carbon pack is to be renewed.

5 To these and other ends, the invention consists in the construction and arrangement of parts that will appear clearly from the following description when read in conjunction with the accompanying drawings, the novel features being pointed out in the claims following the specification.

In the drawings:

Fig. 1 is a plan view, partially broken away, showing a carbon paper pack attached to a flexible holder in accordance with a preferred embodiment of the invention, the holder being mounted on a supporting bar of a carbon paper carriage;

15 Fig. 2 is a plan view, partially broken away, of the flexible holder attached to the supporting bar, with the carbon paper pack removed;

20 Fig. 3 is a sectional view taken on the line 3—3 of Fig. 2 looking in the direction indicated, the carbon paper pack being removed;

25 Fig. 4 is a plan view of the carbon paper pack looking toward the upper side thereof when in operative position for withdrawing a sheet of carbon paper;

30 Fig. 5 is a view similar to Fig. 4, looking at the opposite face or toward the backing sheet of the carbon paper pack;

35 Fig. 6 is a side elevation, partially broken away, of the structure shown in Fig. 4, and

Fig. 7 is a detail side elevation, partially broken away, showing the forward portion of the carbon paper pack with the outermost carbon sheet withdrawn for use.

Referring more particularly to the drawings in which like reference numerals refer to the same parts throughout the several views and to Figs. 4 to 7 inclusive, the carbon paper pack includes a backing sheet 1 to which a multiplicity of carbon sheets 2 are secured at their forward edges, the forward portion of the backing sheet being folded around the forward aligned ends of the carbon sheets as shown at 3 and stitched thereto as at 4. Each carbon sheet is folded upon itself outwardly and the free ends of the folded carbon sheets terminate in spaced relation to the line of stitching 4, as illustrated in Figs. 6 and 7, and thus the carbon sheets can be individually and successively grasped by the operator and withdrawn for use, as shown in Fig. 7, it being understood that the reserve carbon sheets which are not in use are retained in the pack, only one carbon sheet being

used at a time as usual in this type of construction.

The carbon sheets may be attached to the backing sheet 1 in other ways than as specifically herein shown and described, and the backing sheet is preferably of sufficient length to extend around the folded ends of the carbon sheets and to afford a protective cover or flap 5 that overlies the exposed carbon surface of the outermost carbon sheet, as illustrated in Fig. 6.

Various types of carbon paper packs have been detachably associated with a holder, including a pack consisting of a continuous sheet of carbon paper wound around a support, but there has not been heretofore available a structure for detachably mounting on a flexible holder a carbon pack comprising a multiplicity of individually folded carbon sheets arranged flatwise, which is a most convenient and desirable type of carbon pack, and the present invention has to do with detachably mounting such a carbon pack on a flexible holder that can be permanently attached to a supporting bar of the carbon paper carriage.

In order to accomplish this, the backing sheet 1 of the carbon pack has attached thereto a cardboard strip that is stitched to the backing strip along the line 6, see Figs. 5 and 6, the cardboard strip being free from the backing strip except at the stitching line 6, and including an elongated tongue 7 preferably extending across the width of the backing sheet and cut away at its corners as indicated at 8, while 9 designates a finger having tapered sides 10 and arranged centrally of the portion 11 forming part of the cardboard strip, the tongue 7 and finger 9 constituting the means for detachably associating the backing sheet of the carbon pack with the holder which will now be described. It is also within the purview of the invention to form the tongue 7 and finger 9 as integral parts of the backing strip, which may be attached directly to the holder, without the necessity of a separate cardboard strip.

The holder is preferably constructed of canvas or other suitable fabric and includes a body portion 12 folded upon itself to afford a loose flap 13 that overlies the outer surface of the carbon pack when in operative position, the portions 12 and 13 of the holder being stitched together at 14 to afford a hem or loop that receives the supporting bar 15 of the carbon paper carriage. When the flexible holder is once mounted on the supporting bar 15 by sliding the latter through the hem or loop, the flexible holder remains permanently thereon and the carbon paper pack is detachably mounted on the holder as will now be described.

To accomplish this, the opposite end of the flexible holder is folded upon itself as indicated at 16, and 17 designates a band extending across the flexible holder and spaced slightly therefrom as shown in Fig. 3, the ends of the band 17 being folded between the body portion 12 and the folded portion 16 of the holder, as indicated at 18, and adhesively secured in such position, so that the band 17 is permanently located in relation to the holder as illustrated, while 19 designates a slot formed in the folded portion 16 above the band 17.

The folded portion 16 is adhesively attached to the body portion 12 of the flexible holder at the lower portion below the band 17 and along its upper edge above the slot 19, but is free from the body portion 12 immediately adjacent to the slot 19 in order to permit insertion through the

slot of the finger 9, which lies between the body portion 12 of the holder and the folded portion 16 when the carbon paper pack is attached, as shown in Fig. 1, while the space between the band 17 and the folded portion 16 of the holder is occupied by the elongated tongue 7.

In order to attach the carbon paper pack to the holder, the flap 13 is swung outwardly to permit access to the band 17 and slot 19. The carbon paper pack is then positioned over the holder with the tongue 7 and finger 9 in position for insertion under the band 17 and into slot 19 respectively. The elongated tongue 7 is first inserted under the band 17 and between the band 15 and the folded portion 16 of the holder, after which the finger 9 is inserted through the slot 19 into the space immediately above the slot 19 between the body portion 12 of the holder and the overlying folded portion 16.

These surfaces are not adhesively attached at this point so that the tongue can be inserted readily between them, and it will be understood that the tongue 7 and finger 9 being portions of a cardboard element are sufficiently flexible so that they can be bent sufficiently for insertion into their respective locking positions without permanent distortion. When the tongue 7 and finger 9 have been thus inserted, as illustrated in Fig. 1, the carbon paper pack is securely mounted on the holder which in turn is permanently mounted on the supporting bar 15, and the pack is in position for withdrawing the carbon sheets successively to operative position. When all of the carbon sheets in the pack have been exhausted, the carbon pack is removed from the holder by bending finger 9 sufficiently to withdraw it from the slot 19 and then elevating the tongue 7 from behind the band 17. In this fashion, the carbon pack is removed and a fresh pack can be inserted.

While the invention has been described with relation to the particular construction shown, it is not restricted to the details herein disclosed and this application is intended to cover such modifications or departures as may come within the purposes of the invention and the scope of the following claims.

I claim:

1. The combination with a flexible holder that is permanently attachable to a supporting bar of a manifolding typewriter, of a carbon paper pack consisting of a backing sheet and a series of folded carbon paper sheets each attached at one end to the backing sheet, said flexible holder including a fabric support of approximately the width of the carbon paper pack, a band carried by the fabric support and spaced therefrom, the ends of said band extending to the side edges of the fabric support and permanently attached thereto, and said flexible holder having a slot therein, and tongue and finger means on the backing sheet detachably and interlocking engageable with said band and slot respectively of the flexible holder.

2. The combination with a flexible holder that is permanently attachable to a supporting bar of a manifolding typewriter, of a carbon paper pack consisting of a backing sheet and a series of folded carbon paper sheets each attached at one end to the backing sheet, said flexible holder including a fabric support of approximately the width of the carbon paper pack, a band carried by the fabric support and spaced therefrom, the ends of said band extending to the side edges of the fabric support and permanently attached

thereto, said fabric support having a slot therein spaced rearwardly from said band, and an elongated tongue and a finger carried by the backing sheet, said tongue being engageable between said flexible support and said band and said finger being engageable in said slot for attaching the carbon paper pack to said flexible holder.

3. The combination with a flexible holder that is permanently attachable to a supporting bar of a manifolding typewriter, of a carbon paper pack consisting of a backing sheet and a series of folded carbon paper sheets each attached at one end to the backing sheet, said flexible holder including a fabric support of approximately the width of the carbon paper pack, a band carried by the fabric support and spaced therefrom, the ends of said band extending to the side edges of the fabric support and permanently attached thereto, said fabric support having a slot therein spaced rearwardly from said band, and tongue and finger means on the backing sheet detachably and interlockingly engageable with said band and slot respectively.

4. The combination with a flexible holder that is permanently attachable to a supporting bar of a manifolding typewriter, of a carbon paper pack consisting of a backing sheet and a series of folded carbon paper sheets each attached at one end to the backing sheet, said flexible holder including a fabric support of approximately the width of the carbon paper pack, a band carried by the fabric support and spaced therefrom, the ends of said band extending to the side edges of the fabric support and permanently attached thereto, said fabric support having a slot therein spaced rearwardly from said band, and a cardboard strip attached to the outer face of said backing sheet and including an elongated tongue engageable between said flexible support and said band and a finger engageable in said slot of the flexible support for attaching the carbon paper pack to said flexible holder.

5. The combination with a flexible holder that is permanently attachable to a supporting bar of a manifolding typewriter, of a carbon paper pack consisting of a backing sheet and a series of folded carbon paper sheets each attached at one end to the backing sheet, said flexible holder

including a fabric support of approximately the width of the carbon paper pack, a band carried by the fabric support and spaced therefrom, the ends of said band extending to the side edges of the fabric support and permanently attached thereto, said fabric support having a slot therein spaced rearwardly from said band, an elongated tongue and a finger carried by the backing sheet, said tongue being engageable between said flexible support and said band and said finger being engageable in said slot for attaching the carbon paper pack to said flexible holder, and a protective cover carried by said flexible holder and positionable over the inner end of the carbon pack and holder.

6. The combination with a flexible holder that is permanently attachable to a supporting bar of a manifolding typewriter, of a carbon paper pack consisting of a backing sheet and a series of folded carbon paper sheets each attached at one end to the backing sheet, said flexible holder including a fabric support of approximately the width of the carbon paper pack, a band carried by the fabric support and spaced therefrom, the ends of said band extending to the side edges of the fabric support and permanently attached thereto, said fabric support having a slot therein spaced rearwardly from said band, a cardboard strip attached to the outer face of said backing sheet and including an elongated tongue engageable between said flexible support and said band and a finger engageable in said slot of the flexible support for attaching the carbon paper pack to said flexible holder, and a protective cover carried by said flexible holder and positionable over the inner end of the carbon pack and holder.
